CLAIM

The ornamental design for a concealment box, as shown and described.

DESCRIPTION

FIG. 1 is a perspective view of a concealment box in a closed configuration, showing my new design;

FIG. 2 is a top plan view thereof;

FIG. 3 is a front elevation view thereof, with the rear elevation view being a mirror image;

FIG. 4 is a left side elevation view thereof;

FIG. 5 is a right side elevation view thereof;

FIG. 6 is another perspective view thereof, shown in an open configuration;

FIG. 7 is a left side elevation view thereof;

FIG. 8 is a right side elevation view thereof; and,

FIG. 9 is a front elevation view thereof.

All surfaces not shown form no part of the claimed design.

1 Claim, 5 Drawing Sheets
